CHARLES CAILLE, OF LE PERREUX, FRANCE, ASSIGNOR TO L. HUFFER & CIE., OF PARIS, FRANCE.

CONTRIVANCE FOR FEEDING LOCOMOTIVE AND OTHER BOILERS WITH HOT WATER.

1,179,071.

Specification of Letters Patent.

Patented Apr. 11, 1916.

Application filed January 10, 1911. Serial No. 601,770.

To all whom it may concern:

Be it known that I, CHARLES CAILLE, a citizen of the Republic of France, residing at 24 Rue de la Gaité, Le Perreux, Seine, France, have invented new and useful Improvements in Contrivances for Feeding Locomotive and other Boilers with Hot Water, of which the following is a specification.

10 The present invention relates to apparatus for feeding locomotive and other boilers with hot water.

In installations for feeding steam generators, in which installations use is made 15 of the steam exhausted from the engine or of the hot gases escaping up the chimney, it is advantageous for the heating contrivance to be subjected to a pressure as low as possible, for the construction is thus 20 facilitated as is also cleaning, the adherence of deposits (scale and the like) being lessened. Also the vapor is more easily condensed. On the other hand the feeding device (the pump) should be adapted to perform 25 its functions whatever may be the temperature of the water previously heated, and to facilitate working, it is preferable for the pump to be placed on a level lower than that of the receiver from which is 30 drawn the water which is fed to the steam generator. The cold water reservoir 4 and the feed pump 2 are therefore arranged as shown diagrammatically in Fig. 1. Further, this pump should be placed in as low 35 a position as possible, and the heater arranged on a level with the source of cold water 4 (the tender for example). But it is often very difficult to fulfil these conditions, particularly in dealing with locomotives.

The new contrivance permits a steam generator to be fed with water previously heated, whatever may be the relative levels of the three elements, the cold water reservoir 4, the heater *p* and the pump 2.

The contrivance consists in principle, as shown diagrammatically in Fig. 2, in combining the feed pump 2, interposed between the heater and the generator, with a second pump 1 interposed between the heater *p* and the cold water reservoir 4, the two pumps working in synchronism and in opposite directions, that is to say, the evacuation stroke of one coinciding with the inlet stroke of the other, and vice-versa. The

result of this arrangement is that the two conjugate pumps 1, 2 between which is the heater, and which work, the one numbered 1 with cold water, the other 2 with hot water, can be placed on any level relatively 60 to the heater and to the reservoir 4, the heater itself occupying any position relatively to the reservoir.

In practice the conjunction of the two pumps with the heater interposed between 65 them can be carried out in a variety of ways. By preference the arrangement employed is the one shown as a representative example in the annexed drawing and comprising a pump with a single piston operating with two pump chambers, each provided with a complete set of valves (suction and delivery valves), one of the pump elements being fed with cold water from the tank or tender and the other with hot water. 70

Figure 1 is a diagrammatic view of a combined heater and feeder. Fig. 2 is a diagrammatic view of a combined heater and feeder embodying the present invention. Fig. 3 is an elevation partly in section of 80 this special pump and its connections with the cold water reservoir, the heater and the generator to be fed. Fig. 4 is a longitudinal section, the section of the pump being taken along A—A of Fig. 3, and of the valves 85 along B—B of the same figure.

In the example shown, the apparatus comprises a pump *a* divided by a single piston *b* into two compartments 1, 2 which communicate respectively with the valves 90 *c*, *d*. The chamber *e* of the valve box *c* can communicate through the medium of the valves *f*, *g* respectively with the inlet passage *h* and the delivery passage *i*. The chamber *j* of the valve box *d* can be put into communication, through the medium of the valves *k* and *m* respectively with the inlet passage *n* and the delivery passage *o*. 95

In Fig. 3, *p* represents a heater of any known form in which the heating fluid enters through the pipe *q* and escapes through the pipe *r*; *s* represents the exit for the heated liquid; *t* is a motor of any known form for driving the pump. The compartments 1 and 2 constitute two pump chambers; the one numbered 1 in the example shown, is fed with cold water from a reservoir (not shown) by means of a pipe *u* which leads into the inlet passage *h*, the delivery passage *i* being connected by a pipe *v* to a 100

105

110

branch *w* of the heater *p*. The other pump element 2 is in this case fed with hot water from the heater *p* by a pipe *x* leading to the passage *n*, the delivery passage *o* being connected by a pipe *y* to the steam generator. It is obvious that the feeding of the chamber 1 with cold water will take place under all circumstances and without the least difficulty whatever may be the position of the chamber *a* in relation to the cold water reservoir. That is evident for a locomotive as the differences in level are very limited; of course with a stationary installation the difference in level should not exceed the limit allowed, from 7 to 8 meters. The delivery into the heater is accomplished in a similar manner and without the least difficulty in every case. It should be observed that the heater forms in reality a passage in which the water forced from the pump chamber 1 to the chamber 2 circulates and that consequently the level which this passage occupies in relation to the passage *n* matters but little. In the drawing the heater *p* is shown above the passage, but it might just as well be disposed beneath.

The action of the apparatus is as follows: The piston *b* is assumed to be in the position shown in the drawing and to be moving upwardly. It draws in at *h* cold water coming from the reservoir by the pipe *u*, and which, raising the valve *f*, enters the chamber *e*, and flows through the passage *z* into the chamber 1. At the same time the piston *b* by its upper surface drives out the heated water which filled the chamber 2, which water by means of the passage *3*, the valve *m*, the passage *o* and the pipe *y* finds its way to the generator. In its down stroke, the piston draws heated water from *p* through *x-n-k-j-3* while from below it drives out the water which filled the chamber 1, and which is delivered to the heater through *z-e-g-i-v-u*. By reason of the volume of the rod of the piston *b* the chamber 2 has, in the example shown, a smaller capacity than the chamber 1, so that from the difference in delivery of the two pumps there might result an excess of pressure in the heater. In order to provide for this, the pipe *v* must be provided with an overflow branch pipe of a section that can be regulated, the overflow water being conducted to the inlet of the cold water pump.

In practice, particularly in the application of the invention to locomotives, it is advantageous to diminish the length of the various systems of pipes as much as possible; in order to avoid superpressure in the heater or to maintain a pressure less than one atmosphere for example on the walls, the pipe *v* is directly connected to the pipe *u*. But then it is necessary to prevent any premature admission which would tend to take place directly from *v* to *u* owing to the

vacuum existing in the latter pipe at the moment of admission. It is the achievement of this result which the contrivance illustrated in Fig. 5 illustrates. As shown in this figure the pipe *v*, which conducts cold water to the heater is connected to the pipe *u* by means of a valve-box 6 and a pipe 11. The valve-box 6 contains a valve, represented in the drawing as a piston valve 7 formed with openings 8. This valve rests on a valve 9 of smaller diameter, held on its seat by a spring 10 of strength such that the valve 9 cannot move from its seat even if there exists in the pipe *u* a complete vacuum, and so long as the pressure in the heater does not exceed the maximum limit selected. When this limit pressure is reached, the piston valve 7, owing to its greater diameter, is able to displace the valve 9 and uncover the openings 8. A certain quantity of water then passes from *v* to *u* until the pressure in the heater falls to the maximum value selected.

The piston *b* is preferably constructed as shown in Fig. 4. The minimum height of this piston should be at least as great as the length of the stroke, in order to prevent a portion of the chamber *a* being alternately in contact with the hot and the cold water. In addition, the piston is made in two parts separated by a ring 5 of insulating material, in order to prevent any transmission of heat from the upper to the lower part, the two parts working respectively in a warm water and a cold water chamber. The same construction of two parts insulated from one another can evidently be applied to the pump cylinder *a*.

I claim:

1. In a boiler feeding apparatus, a heater, a double-acting suction pump comprising a cylinder and a piston operating in said cylinder, a supply pipe leading to one end of the pump cylinder, a second pipe leading from the same end of the pump cylinder to the heater, a third pipe leading from the heater to the opposite end of the cylinder, a boiler pipe leading from the last-named end of the cylinder, a non-return check valve provided in each pipe connection, and a compensating valve including a casing connecting the supply pipe with the second pipe, a valve member adapted to seat within the casing, resilient means for maintaining the said valve member seated against the action of decreased pressure within the supply pipe, and a second valve member adapted to seat within the casing on the side of the first valve member adjacent to the second pipe and being associated with the first member so as to open the same upon being opened by increased pressure within the said second pipe.

2. In a boiler feeding apparatus, a heater, a double-acting suction pump comprising a

cylinder and a piston operating in said cylinder, a supply pipe leading to one end of the pump cylinder, a second pipe leading from the same end of the pump cylinder to the heater, a third pipe leading from the heater to the opposite end of the cylinder, a boiler pipe leading from the last-named end of the cylinder, a non-return check valve provided in each pipe connection, and a compensating 5 valve including a casing connecting the supply pipe with the second pipe, a valve member adapted to seat within the casing, resilient means for maintaining the said valve member seated against the action of decreased pressure within the supply pipe, and 10 a second valve member adapted to seat within the casing on the side of the first 15

valve member adjacent to the second pipe and being associated with the first member so as to open the same upon being opened 20 by increased pressure within the said second pipe, the second valve member being constructed to present a greater area of effective surface to the water within the second pipe than the first valve member presents to the water within the supply pipe. 25

In testimony whereof I have signed my name to this specification in the presence of two subscribing witnesses.

CHARLES CAILLE.
